No. 723,752.

PATENTED MAR. 24, 1903.

F. STICKER.
STEAM INJECTOR.

APPLICATION FILED MAY 2, 1902.

MODEL.

UNITED STATES PATENT OFFICE.

FRANCIS STICKER, OF NEW YORK, N. Y., ASSIGNOR TO CHARLES A. DRUCKLIEB, OF NEW YORK, N. Y.

STEAM-INJECTOR.

SPECIFICATION forming part of Letters Patent No. 723,752, dated March 24, 1903.

Application filed May 2, 1902. Serial No. 105,651. (Model.)

To all whom it may concern:

Be it known that I, FRANCIS STICKER, of New York, in the county of New York and State of New York, have invented certain new 5 and useful Improvements in Steam-Injectors; and I do hereby declare the following to be a full, clear, and exact description of the invention, such as will enable others skilled in the art to which it appertains to make and use 10 the same.

The object of this invention is to provide a steam-injector designed especially for motor-vehicles. It is well known that great difficulty is experienced in supplying the boilers 15 of motor-vehicles with water while such vehicles are in operation and that owing to the speed at which they travel and the necessity for employing light-weight machinery the ordinary injectors, even of the smallest type 20 heretofore known, are not adapted for such service, for, aside from their weight, it is impossible to prevent breakage of the jet or column if the injector is brought into operation while the machine or vehicle is in motion.

25 By my invention I provide an injector of very light weight, occupying but little space, but capable of supplying boilers with water without danger of any break occurring in the jet or column of water no matter at what 30 speed the vehicle may be traveling.

The invention will be hereinafter fully set forth, and particularly pointed out in the claims.

In the accompanying drawings, Figure 1 is 35 a vertical longitudinal sectional view. Fig. 2 is a slightly-enlarged cross-sectional view on line 2 2, Fig. 1. Fig. 3 is a similar view on line 3 3, Fig. 1, looking in the direction of the delivery end of the injector.

40 Referring to the drawings, 1 designates the casing, having at one side the water-inlet opening 2, at its under side the steam-inlet opening 3 and boiler-outlet 4, while at its extreme end is the overflow-outlet 5. Extending 45 through the steam-chamber 6 is a double steam-tube 7—that is, from the central open or lantern-like portion of this tubular body extend the steam-tube 8 of the lifter and the steam-tube 9 of the forcer, the former extending rearward and the latter forward in 50 axial line with each other. In line with the

lifter steam-tube 8 is the combining-tube 10, which empties into the discharge-chamber 12 of the lifter, which chamber is connected by an upper longitudinal channel 13, extending 55 throughout the length of the casing, with the transverse opening wherein fits the controlling-cock 14, preferably of the type employed in the injectors known to the trade as the "Easy."

60 The steam-tube 9 of the forcer opens into the water-chamber 15 of the forcer, which chamber derives its supply from channel 13. In line with this steam-tube is the combining and delivery tube 16 of the forcer, which tube 65 has an overflow spill-slot 17, through which the initial overflow passes into overflow-chamber 18. The tube 16 opens into the discharge-chamber 19, which connects with both the boiler-outlet and the opening wherein cock 70 14 is located. This cock has three ports, registering, respectively, with the channel 13, the overflow-chamber 18, and the discharge-chamber 19. These ports are, as usual, relatively arranged, so that in turning the cock 75 the initial overflow from channel 13 will be first cut off, then the overflow from chamber 18, and then the outlet from chamber 19, whereupon the established jet or column of water will pass to the boiler through the outlet 80 14.

For the purpose of regulating the quantity of water to be fed to the boiler—that is, to control the working of the injector—I provide a throttle in the form of a tapered needle-like 85 rod 20, secured to a screw-rod 21. By turning the latter the rod 20 will be extended into the combining-tube of the lifter, and thereby regulate the volume of water discharged therefrom. The extent to which the water is 90 throttled is controlled by the extent to which the tapered rod is projected into the combining-tube.

In practice the steam entering the steam-chamber and passing through the open portion of the tubular body 7 will enter the two steam-tubes, that passing through the lifter steam-tube finding its way to the atmosphere through channel 13, while that passing through the forcer steam-tube will reach the 95 atmosphere either through the same channel or through chambers 18 and 19, or all of them.

The steam upon reaching the atmosphere will effect the lifting of the water into the water-chamber of the lifter, which water passing through the lifter combining-tube will travel 5 through channel 13. When the column is established, all overflow is cut off by the turning of cock 14, and such column will thereupon pass to the boiler through the outlet 4.

An injector constructed in accordance with 10 my invention is of but minimum weight, and the tubes of the lifter and forcer being in the same axial line and having a common source of steam-supply occupy but little space, and hence the size of the injector is made to fill 15 the requirements insisted upon in motor-vehicle construction. The injector is capable of easy manipulation and will supply water to a boiler without any break in the jet or column regardless of the speed at which the 20 vehicle may travel. Once the steam is admitted the working of the injector depends merely upon the turning of the cock, while the quantity of water discharged may be regulated by the turning of the throttle.

25 I claim as my invention—

1. A steam-injector having the tubes of the lifter and forcer arranged in the same axial line for handling the steam and water in opposite directions, and a passage-way between 30 the discharge-chamber of the lifter and the water-chamber of the forcer, as set forth.

2. A steam-injector having the tubes of the lifter and forcer arranged in the same axial line, the steam-chamber being common to the 35 steam-tubes of both the lifter and forcer, and a passage-way between the discharge-chamber of the lifter and the water-chamber of the forcer, as set forth.

3. A steam-injector having the steam-tubes 40 of the lifter and forcer in axial line with each other and leading from a common steam-chamber, the combining-tube of the forcer leading from the water-chamber, and a passage-way connecting the lifter discharge-chamber with the forcer water-chamber, and the combining and delivery tube of the forcer 45 in line with its steam-tube, as set forth.

4. The casing having at one end a lifter discharge-chamber, at or near the other end an 50 overflow-opening, a channel or passage-way connecting such chamber with such opening,

the forcer water-chamber being supplied from said channel, the tubes of the lifter and the tubes of the forcer, the former discharging into said discharge-chamber and the latter 55 handling the water from the water-chamber of the forcer, and means for cutting off the overflow, substantially as set forth.

5. The combination with the casing having a steam-chamber, a discharge-chamber at one 60 end, an overflow-opening at the other end, and a channel or passage-way connecting said discharge-chamber with said opening, of the tubes of the lifter and forcer, arranged in axial line with each other, the two steam- 65 tubes leading in opposite directions from said steam-chamber, the water-chamber of the forcer being open to said channel, and means for closing the overflow, substantially as set forth.

6. A steam-injector having lifter-tubes and forcer-tubes, and means for regulating the discharge of the lifter, such means controlling the outlet of the combining-tube thereof, as 70 set forth.

7. A steam-injector having lifter-tubes and forcer-tubes, and means for regulating the discharge of the lifter, such means comprising a throttling-rod extended into the combining-tube of the lifter, as set forth.

8. A steam-injector having the tubes of the lifter and the tubes of the forcer arranged in the same axial line for handling the steam and water in opposite directions, and a throttling-rod extended into the combining-tube of the 85 lifter for regulating the discharge of the latter, as set forth.

9. A steam-injector having the tubes of the lifter and forcer arranged in the same axial line for handling the steam and water in opposite directions, a passage-way between the discharge-chamber of the lifter and the forcer water-chamber, and a throttle-rod extended 90 into the combining-tube of the lifter, as and for the purpose stated.

In testimony whereof I have signed this specification in the presence of two subscribing witnesses.

FRANCIS STICKER.
